UNITED STATES PATENT OFFICE

1,989,612

FURNACE

Luis de Florez, Pomfret, Conn., assignor to The Texas Company, New York, N. Y., a corporation of Delaware

Application July 13, 1931, Serial No. 550,356

8 Claims. (Cl. 122—356)

My invention relates to furnaces, more particularly to tubular oil heaters used in processes involved in the heating and cracking of oils, and has for its principal object the provision of a furnace of the upshot type in which a fluid such as oil either in liquid or vaporous form can be thoroughly and uniformly heated in a minimum of time.

A further object of my invention is the provision of novel supporting structure for the vertical tubes by means of which the weight of the tubes is carried by the lower supporting structure of the furnace while provision is made for longitudinal contraction and expansion of the tubes caused by the heating and cooling thereof.

In vertical draft furnaces in which a plurality of parallel, heating tubes are arranged uniformly around a heating flame it is sometimes difficult to secure a uniform heating throughout the full length of the tubes. When the jet or flame is located at the level of the floor or lower wall of the heating chamber and the flame and hot products of combustion are directed upwardly through the space surrounded by the vertical tubes, the lower portions of the tubes sometimes remain cooler than the center or upper portions. Consequently it is essential that there be complete combustion of the gases near the bottom of the vertical tube section with greater turbulence and mixture of the gases without impingement of the flame on the tubes.

In carrying out my invention I have provided a burner mounted near the lower end of a refractory well, preferably cylindrical or conical in shape and arranged in a firebox below the floor or lower wall of the vertical tube section. Air to be burned with the fuel is admitted to the firebox and passes upwardly to the burner. The air for combustion, after entering the firebox surrounds the well and tends to cool the latter. With this construction the products of combustion are directed upwardly through the tube section, this causing a uniform heat distribution to the full length of the tubes since the temperatures at the inlet and outlet of the tubes are more nearly equal. There will be greater uniform radiation since the column produced by the products of combustion is at its maximum volume and regular in circumference in the lower portion of the heating chamber.

In furnaces of this type wherein the vertical tubes are suspended from their upper extremities it is necessary to specially design the upper part of the furnace to take care of this added weight. Therefore, in further carrying out my invention

I have provided means whereby the tubes are supported from their lower ends thus allowing the entire weight of the tubes to be carried by the lower structure of the furnace while at the same time, provision is made to allow the tubes to contract and expand upwardly without deformation. By supporting the tubes at the bottom the furnace is rendered more stable and the expense of construction is minimized.

For a better understanding of my invention reference may be had to the accompanying drawings in which Fig. 1 is a vertical, sectional elevation of a furnace embodying my invention; Fig. 2 is a sectional view taken on line 2—2 of Fig. 1 looking in the direction of the arrows; Fig. 3 is an enlarged view showing one form of construction at the lower ends of the tubes; Fig. 4 is a view taken on line 4—4 of Fig. 3, while Figs. 5, 6 and 7 are detail views of a modified form of tube supports, Fig. 5 being a sectional elevation on line 5—5 of Fig. 6, Fig. 6 a horizontal section on line 6—6 of Fig. 5 and Fig. 7 a side elevation of the supporting ring.

Referring to Fig. 1 of the drawings, I have illustrated a vertical draft furnace of the upshot type, having a firebox 10, a vertical tube section 11, an economizer 12 and an air preheater 13. The firebox 10 is supported on a suitable base 14, while a metal framework 15 serves to support the tube section 11 and the upper part of the furnace structure. The tube section 11 comprises refractory top, bottom and side wall defining a heating chamber 16, the side walls being provided with linings 17 of suitable heat insulating material. The top wall 18 and the bottom wall 19 are formed of suitable heat resisting metal and leading upwardly from the center of the top wall 18 is a flue 20, this flue serving to conduct the hot gaseous products of combustion from the heating chamber 16 through the economizer section 12 and then upwardly through a plurality of tubes 21 in the air preheater 13, after which the gases pass to a stack 22. It is to be understood that air for combustion enters the preheater 13 through an inlet 23 after which it circulates back and forth around suitable baffles 24 and the tubes 21, finally leaving the preheater through the outlet 25 and passing into the firebox 10 through an inlet 26. In the tube section 11 a plurality of heating tubes 27 are mounted and are supported from the bottom wall 19 in a manner which will be described hereinafter. It is to be understood that the tubes 27 are intended to be heated by means of a column of hot products of combustion which passes upwardly through the center of the

chamber 16 and which is of a size and shape such that there will be no impingement of the flame on the heating tubes.

It is quite common in a furnace of this general type to mount the burner or burners substantially at the level of the bottom wall such as the wall 19, or when mounting the burners below the level of the bottom wall, to make no provision for the admixture of air with the gas or other fuel below the bottom wall to secure efficient and complete initial combustion, so that the size of the hot products of combustion column will be as great in the lower portion of the chamber 16 as it will be at a point some considerable distance above the bottom wall. In carrying out my invention I have provided a refractory well 28 arranged within the firebox 10 and leading upwardly to the center of the lower wall 19. The well 28 is preferably of a frustro-conical shape and is formed of a layer or layers of suitable refractory material supported by a shell 29 of heat resistant metal.

At points located near the lower end of the well 28 I have provided a plurality of burners 30, these burners being connected to a ring or conduit 31 and entering the well 28 substantially tangentially of the surface thereof as shown more clearly in Fig. 2. The ring 31 is adapted to be connected to a suitable source of fuel supply such as gas or fuel oil by means of a pipe 32. Due to the tangential arrangement of the burners 30 the fuel entering the well will, in burning, pass upwardly, therethrough in a spiral, thus increasing the turbulence and providing a more intimate mixture. The air entering the firebox 10 through inlet 26 will pass upwardly into the lower end of the well 28 where it will be burned with the gas at the burners 30. The air entering the firebox will circulate around the outer surface of the shell 29 and will have a cooling effect on the well 28. While I have illustrated burners suitable for gas or liquid fuel, it is to be understood that my invention is not to be limited thereto since burners for injecting powdered fuel can readily be used in place of the burners 30. It will be observed that by locating the burners 30 at a point below the level of the bottom wall 19 the column of hot products of combustion will reach substantially its maximum diameter in the lower portion of the chamber 16 and consequently the lower portions of the tubes 27 will receive the benefit of this large column and the tubes will be heated quite uniformly throughout their entire lengths.

In furnaces of this general type it is quite common to suspend the vertical tubes from their upper ends and to have no rigid contact between the lower ends of the tubes and the bottom wall of the furnace, thus providing for expansion and contraction of the tubes due to heat variations. However, with such a construction it is necessary that the upper part of the furnace, where the top ends of the tubes are located, be of heavy construction in order to withstand the total weight of the tubes. In order to do away with the necessity for this heavy construction I have provided novel mounting means for the tubes 27 by means of which the entire weight of the tubes is transmitted directly to the bottom wall 19 of the tube section and thus to the lower supporting framework or structure of the furnace. I have illustrated in Figs. 3 and 4 one form of supporting structure and in Figs. 5, 6 and 7 a modified form.

With reference to Figs. 3 and 4 I have provided each tube 27 at a point near the lower end there- 75 of with an annular groove 33 and a washer ele-

ment 34 formed of two similar sections is arranged to be partially inserted in this groove. A ring or flanged member 35 has a sliding engagement with the tube 27 and is adapted to rest upon the upper surface of the bottom wall 19 and surround a hole 36 through which the tube 27 may be inserted. One side of the ring member 35 is cut out as shown at 37 and is adapted to encompass the two sections of the washer element 34 after these sections have been placed in the groove 33. 10 As will be observed with reference to Fig. 3 the entire weight of each tube is transmitted through the washer element 34 to the member 35 and then to the bottom wall 19 of the heating chamber 16. 15

The heating tubes 27 may be connected in multiple or in series, or in groups connected in multiple and these groups then connected in series. In order to connect the ends of the tubes together suitable junction boxes 38 are provided, these boxes being adapted to engage the extremities of 20 the tubes and each box having a chamber 39 through which the fluid to be heated is passed from one tube to another. The junction boxes are preferably provided with plugs 40 which may be removed to permit the cleaning of the tubes 27. 25 The lower ends of the tubes 27 and the junction boxes 38 are contained within an annular chamber 41 secured to the underside of the bottom wall 19. The annular chamber 41 is provided with a removable closure member 42 so that access may 30 be had to the junction boxes. The upper ends of the tubes 27 pass through openings, not shown, in the top wall 18 of the heating chamber and have a sliding fit in the top wall so that the tubes may freely expand or contract in a vertical direction due to heat variations. The upper ends of the tubes 27 are provided with similar junction boxes 43, these boxes being contained within an annular chamber 44 provided with a removable closure 45 to allow access to the junction boxes. 40

It is to be understood that the fluid to be heated enters the economizer 12 through an inlet 46 and after being heated in the tubes 47 leaves the economizer through an outlet 48 and passes directly to one or more of the heating tubes 27. 45

In Figs. 5, 6, and 7 I have shown a modified form of supporting means for the tubes 27. In this form a washer element 49 is rigidly secured to a tube 27 such as by welding at 50. A flanged or wheel-shaped member 51 formed of two sections 51a and 51b is adapted to rest upon the bottom wall 19 in a manner similar to that described with reference to the ring member 35 shown in Fig. 3, while the washer 49 is adapted to be supported in a cutout portion 52. The sections 51a and 51b are provided with other cutout portions 53 and these latter serve to permit access to suitable screws or bolts, not shown, adapted to be placed through holes 54 in the sections 51a and 51b. The two sections of the flanged member 51 may 60 thus be assembled about the tube 27 and held together by means of the bolts to form in effect a single element similar to the ring member 35 described hereinbefore. A cutout portion 55 is also provided in the lower part of the member 51 and a flange 56 is thus left on which the washer 49 serving the tube 27 is supported. It will thus be seen that the weight of the tubes 27 is transmitted through the washer 49 and member 51 to the bottom wall 19 of the heating chamber 16. A suitable packing 57 such as asbestos rope may be placed in the space 55, this packing serving to prevent gases from leaking out of the heating chamber 16 around the tube 27. 70

Obviously many modifications and variations 75

of the invention, as hereinbefore set forth, may be made without departing from the spirit and scope thereof, and therefore only such limitations should be imposed as are indicated in the appended claims.

I claim:

1. In a furnace for heating fluids, heat refractory top, bottom and side walls defining a heating chamber, a heating coil comprising a plurality of interconnected tubes disposed vertically in said chamber and passing through said top and bottom walls, and means for supporting each of said tubes only from the bottom wall comprising an element adapted to be affixed to the outside of each tube and a ring member positioned on the lower wall of said chamber and adapted to be engaged by and support said element.
2. In a furnace for heating liquids, heat refractory top, bottom and side walls defining a heating chamber, a heating coil comprising a plurality of interconnected tubes disposed vertically in said chamber and passing through said top and bottom walls, and means for supporting each of said tubes only from the bottom wall comprising a washer element adapted to be affixed to each tube near its lower end, and a flanged member adapted to engage said element and positioned on the bottom wall of said chamber so that the weight of said tubes will be transmitted to said bottom wall through said washer elements and said flanged members.
3. In a furnace for heating fluids, heat refractory top, bottom and side walls defining a heating chamber, a heating coil comprising a plurality of interconnected tubes disposed vertically in said chamber and passing through said top and bottom walls, and means for supporting each of said tubes only from the bottom wall comprising a sectional washer element, each of said tubes being provided with a circumferential groove near its lower end to engage said element and a flanged member adapted to support said washer element and rest upon the bottom wall of said chamber.
4. In a furnace for heating liquids, heat refractory top, bottom and side walls defining a heating chamber, a heating coil comprising a plurality of interconnected tubes disposed vertically in said chamber and passing through said top and bottom walls, and means for supporting each of said tubes only from the bottom wall comprising a

washer element adapted to be affixed to each tube near its lower end, and a flanged member resting on the bottom wall of said chamber and adapted to surround and support said washer element and said tube.

5. In a liquid heating furnace, top, bottom and side walls defining a cylindrical heating chamber, a plurality of heating tubes disposed around the inside of said side walls, each of said tubes passing through said top and bottom walls and means for supporting said tubes only on the bottom wall of said chamber comprising a washer element adapted to be affixed to each of said tubes at a point near its lower end, a sectional flanged member resting on said bottom wall and adapted to engage and support said element and said tube, means for holding the sections of said flanged member together, and means associated with said member for holding a packing material in engagement with said bottom wall and said tube.

6. In an apparatus for heating fluids, a heating chamber, vertical heat absorbing tubes positioned in said chamber, the ends of said tubes passing through and extending outside of the chamber at the bottom thereof and means surrounding said tubes for preventing the passage of gases between the heating chamber and the outside thereof, said means resting upon the bottom of said chamber for supporting the tubes.

7. In an apparatus for heating fluids, a heating chamber, vertical heat absorbing tubes positioned in said chamber, the ends of said tubes passing through and extending outside of the chamber at the bottom thereof and a ring having an asbestos packing surrounding said tubes passing through said chamber to prevent the passage of gases between the heating chamber and the outside thereof, said ring resting upon the bottom of said chamber for supporting the tubes.

8. In a furnace for heating fluids, heat refractory top, bottom and side walls defining a heating chamber, a heating coil comprising a plurality of interconnected tubes disposed vertically in said chamber and passing through said top and bottom walls, and means for supporting each of said tubes from the bottom wall, said means providing a seal between the heating chamber and the outside thereof to prevent the passage of gases therebetween.

LUIS DE FLOREZ. 50
